UNITED STATES PATENT OFFICE.

HOWARD W. HALL, OF WOODBRIDGE, NEW JERSEY, ASSIGNOR TO AMERICAN SMELTING AND REFINING COMPANY, OF NEW YORK, N. Y., A CORPORATION OF NEW JERSEY.

APPARATUS FOR SMELTING.

Application filed July 30, 1925. Serial No. 46,947.

This invention relates to smelting furnaces and methods for the smelting of ores, concentrates and similar materials; and the invention relates particularly to the formation 5 of banks of the charge or material to be smelted so as to constitute one or more of the side and end walls of the furnace and correspondingly minimize furnace maintenance charges. It is advantageous to feed 10 the charge, which is usually in the form of fine concentrates or calcines, into the furnace in such way as to form a substantially air-tight seal with the furnace arch, and in the operation of the furnace the charge as 15 it is smelted from the inner face or portion of these banks of material is replaced from time to time so that a substantially constant renewable bank of the material to be smelted forms the furnace wall and is present in any 20 desired thickness. It is thus possible to control or minimize heat losses and corrosion difficulties, especially since these banks of the charge may extend down into the furnace, hearth or crucible so as to prevent contact between the fused slag and the hearth 25 bottom.

In some cases it is advantageous to use a drum type of feed, and the feeding drums, of which any suitable number are preferably 30 arranged around the sides and end of the furnace chamber, may be independently actuated so as to feed the desired quantities of material into the different zones of the furnace. These drum feeders may force the finely 35 divided charge inward and upward so as to make effective sealing contact with the arch, and where desired the heating burners and cooperating air ducts may extend through the bank of charge at the firing end of the 40 furnace and preferably be sustained more or less throughout their length or inner end as well as supported at their rear end away from the furnace chamber. In many cases it is desirable to have a screw type of feed 45 to handle the finely divided charge, and one or more feed screws may be arranged so as to feed the material into hoppers or receiving chambers that may be located along the one or more sides or ends of the furnace; 50 and in some cases the feed screws may be mounted in slotted tubes or conduits and may extend more or less continuously around the

sides and lower firing end of the furnace so as to continuously supply ample material thereto.

Various other objects and advantages of the invention will be obvious from the following particular description of one form of mechanism embodying my invention or from an inspection of the accompanying drawings; and the invention also consists in certain new and novel features of construction and combinations of parts hereinafter set forth and claimed.

In the following description and in the claims parts will be identified by specific names for convenience of expression, but they are intended to be as generic in their application to similar parts as the art will permit.

In the accompanying drawings I have shown for purposes of illustration one form of mechanism with certain modifications thereof embodying the invention, in which

Fig. 1 is a sectional elevation view taken along the line 1—1 of Fig. 2 showing the charging end of a melting furnace having a hearth formed with a depression therein for receiving molten material and showing ore being fed thereto from each side of said charging end in two broad streams which forms side-walls for material which has been molten, and showing feeding paddle wheels which receive ore charges from chutes positioned near them and which serve to pile the ore up to the furnace roof or arch to cause the ore to form a sidewall which is continuous from the hearth to the roof of arch. The paddles further serve to feed the ore in such a manner that it reaches downwardly into the molten bath to a point below the slag line therein whereby the material of the hearth is protected from any corrosive action of such slag; and

Fig. 2 is a longitudinal view in section through the line 2—2 of the melting end of the furnace shown in the Fig. 1.

In the drawings the furnace base 1 has formed therein the hearth 3 which has the metal receiving depression 4 therein which slants upwardly on the ends as well as the sides to form a longitudinal basin or receptacle. In the charge receiving end which is shown in the drawings, above and to one

side of the hearth there is provided at each side a pair of paddle wheels 6 mounted with their axle parallel to the length of the hearth. An ore passing space 7 between the bottoms 5 of the paddle wheels and the floors or platforms 8 is provided by suitably spacing said wheels above the platforms 8. Suitable means (not shown) are provided for rotating said paddle wheels downwardly and inwardly 10 toward the hearth. Outside the paddle wheels there is provided for each of them a feeding hopper 10 which discharges close to the bottom of and into operative relation with the respective paddle wheels. 15 About the sides and ends of the furnace there is provided in the usual manner a furnace wall 12 which has suitable openings therein for said paddle wheels 6. The furnace is also provided with a suitable roof 14 20 which at the charging end and as shown in the drawings extends laterally into close proximity to said paddle wheels 6, 6 suitable space being allowed for the proper rotation of the paddles. In the preferred forms the 25 blades 16 on the paddle wheels are slanted backwardly and away from the direction of rotation thereof for purpose hereinafter fully described.

As shown in the drawings, the paddle 30 wheels are of such diameter and are so spaced with respect to the several parts of the furnace that when ore is fed to them in proper amounts and the paddles rotated downwardly and inwardly toward the hearth the 35 ore will be carried thereby to form with the roof and walls of the furnace a continuous enclosure. The back slant of the paddle wheel blades provides for the discharging of substantial amounts of charge inside the 40 furnace and from near the top of the wheel whereby the material is caused to pile up from the roof of the hearth and across the feeding openings.

In the regular operation of the furnace 45 above described, a suitable melting atmosphere being provided therein, ore is fed into the hoppers 10, 10, the paddle wheels 6, 6 are rotated downwardly and inwardly toward the hearth of the furnace so ore fed to wheels 50 6 from hoppers 10 is carried through said passage 7 and over the platforms 8. The feeding of the ore is continued through the hoppers 10 to pile it up on the platforms 8 and at the inner sides of the respective 55 paddle wheels 6 until it reaches the top 14 of the hearth whereby there is formed a continuous closure of ore between said platforms 8 and said top 14 thereby closing the space between the paddles 6 and their respective platforms 8 and between the paddles 60 and the roof. By this time the ore has begun to slide from the platforms 8 and from the top of the pile down into the basin 4 of the hearth where metal molten from the 65 ore is accumulated to a desired depth and

drawn off at tap holes provided in the discharge end of the furnace (not shown). During such melting additional ore is fed through the hoppers 10 in such amounts and at such rates as to keep a filling thereof between the platforms 8 and the roof 14. In the charging and melting portion of the hearth and at the bottom of the ore slide therein said ore forms side walls for the metal bath which protects the hearth from the corrosive action of the slag. This wall, of course, continues to be molten but with the continued replenishing of the charge by the paddle wheels the position of the ore wall is kept substantially constant between given 75 limits. As indicated in the drawings the ore, as it slides into the hearth, flows around and laps over the sides of the hearth at these points to form a protective covering therefor. Likewise, the ore streams fed from the 80 respective pairs flow sidewardly as well as transversely to join each other and bridge the space between the wheels of each pair.

Although I have shown and described and have pointed out in the annexed claims certain novel features of my invention, it will be understood that various omissions, substitutions and changes in the several steps of my process and in its operation and in the form and details of the apparatus illustrated 95 may be made by those skilled in the art without departing from the spirit of the invention.

I claim—

1. In a melting furnace having side walls 100 and a roof, and an opening therein, means for feeding a charge to the furnace inwardly and upwardly through said opening and for keeping it piled above said opening while it is moving for forming a closure therefor. 105

2. In combination, in a melting furnace having a hearth, side walls and roof, and an elongated opening in one of its walls, means for feeding a charge to the furnace through the entire width of said opening 110 continuously and for keeping the charge piled up across the opening while it is being fed to form a closure for said opening.

3. In combination with a melting furnace having a hearth, side walls and roof, one 115 of its walls having an opening therein, a paddle wheel mounted outside said opening on a horizontal axis and means for rotating the paddle wheel on its said axis downwardly and inwardly toward the interior of the 120 furnace, the bottom of said paddle wheel being spaced from the bottom of said opening to provide a charge passage thereby, and the top of said wheel extending a substantial distance above the top of said opening. 125

4. In combination with a melting furnace having a hearth, roof and side walls with openings at opposite sides of said furnace, a paddle wheel mounted close to and outside each of said openings for rotation on a 130

horizontal axis in a direction downwardly and inwardly toward the interior of the furnace, said wheel being spaced away from the bottom of said opening to provide a 5 charge passageway thereby, and extending above the top of said opening a substantial distance.

5. In combination with a melting furnace having a hearth, side walls and a roof, one 10 of its walls having an opening therein, a paddle wheel mounted outside said opening on a horizontal axis and means for rotating the paddle wheel on its said axis downwardly and inwardly toward the interior of 15 the furnace, the bottom of said paddle wheel being spaced from the bottom of said opening to provide a charge passage thereby, and the top of said wheel extending a substantial distance above the top of said opening, 20 said hearth being formed with a depression therein having the edge nearest said opening at such a distance therefrom that the charge fed through the opening by said wheel ex-

tends over said edge into the said depression. 25

6. In combination with a melting furnace having a hearth, roof and side walls with openings at opposite sides of said furnace, a paddle wheel mounted outside each of said openings for rotation on a horizontal axis 30 in a direction downwardly and inwardly toward the interior of the furnace, said wheel being spaced away from the bottom of said opening to provide a charge passageway thereby, and extending above the top of 35 said opening an appreciable distance, said hearth being formed with a depression therein having the edge nearest said opening at such a distance therefrom that the charge fed through the opening by said wheel ex- 40 tends over said edge into the said depression.

In testimony whereof I have hereunto set my hand and seal.

HOWARD W. HALL.
